UNITED STATES PATENT OFFICE.

EUGENE MOREHOUSE, OF PROVIDENCE, RHODE ISLAND, ASSIGNOR TO B. A. BALLOU & COMPANY, INCORPORATED, OF PROVIDENCE, RHODE ISLAND, A CORPORATION OF RHODE ISLAND.

SAFETY CATCH.

Application filed February 20, 1922. Serial No. 537,842.

To all whom it may concern:

Be it known that I, EUGENE MOREHOUSE, a citizen of the United States, residing at Providence, in the county of Providence and 5 State of Rhode Island, have invented certain new and useful Improvements in Safety Catches, of which the following is a specification.

This invention relates to a safety catch 10 which is designed to be secured to the body of a pin such as a cuff pin and the like for the purpose of engaging the pointed end of a pin-tongue to fasten the same against being inadvertently released therefrom, and 15 the object of this invention is to provide such a safety catch which is provided with a body portion having an attaching base at one end and a hook-shaped portion at its opposite end, the hook being provided with 20 a groove in its peripheral face for the reception of a guard member which is slidably mounted therein.

With these and other objects in view, the invention consists of certain novel features 25 of construction, as will be more fully described, and particularly pointed out in the appended claims.

In the accompanying drawings.

Figure 1 is a side elevation of my improved safety catch showing the guard member in released or open position.

Figure 2 is a sectional side elevation of a catch showing the guard member in closed position.

Figure 3 is a section on line 3—3 of Figure 1 looking in the direction of the arrow and showing the side flanges forming the groove in the outer face of the hook the edges of which flanges are turned inwardly 40 over those of the guard member to operatively hold the same in position.

Figure 4 is a view of the rear of my improved catch showing the catch in the position illustrated in Figure 1.

Figure 5 is a section on line 5—5 of Figure 1 showing the U-shape of the attaching base portion of the body member.

With reference to the drawings, 10 designates the body member of my improved 50 safety catch which is preferably formed of sheet stock with its side edges folded back upon itself providing a substantially U-shaped base portion 11 at one end thereof and a hook-shaped portion 12 at the opposite end thereof.

By folding the sides of this body member backward the walls 13 thereof form a very broad base which facilitates the attaching of the same by solder or otherwise to any suitable support, such as the back of a brooch, cuff pin and the like and these folded portions serve as side walls 14 about the outer peripheral surface of the hook portion providing a groove in which the guard member 15 is slidably mounted. This guard member is semi-circular in form and may be made in any desired shape in cross section, but I preferably form the same on the arc of a circle and the side flanges 14 of the hook are bent inwardly over the edges 15 of this guard member thereby preventing the guard from opening circularly which would otherwise be the case when strain is brought thereon in sliding the same to and from operating position.

This guard member is provided with an operating handle 16 which extends outwardly radially therefrom and is preferably made narrower than the body of the guard, as illustrated in Figure 4, so as not to interfere with the inwardly-extending side walls of the base portion when forced down therebetween, as illustrated in Figure 1, when moved to open position.

Many advantages are obtained by my improved safety catch over the old style safety catches which had to be swaged into shape; first, the body portion may be made of sheet stock and its sides may be folded back into substantially U-shape thus producing a very strong and durable structure; second, by folding the side walls of the hook portion over the edges of the guard member the guard is effectually prevented from opening up or spreading circularly 95 to a larger diameter and is effectually prevented from being removed from its hook-shaped bearing surface and lost; third, the edge flanges about the hook serve to stiffen and give to the hook greater strength thereby permitting the whole device to be made of very light weight stock which is of considerable advantage particularly where the catches are made of the precious metals; fourth, by mounting the guard on the outside circumference of the hook sufficient frictional area is presented to the guard to prevent it from moving from its adjusted positions thus obviating the necessity of employing detents for this purpose.

The device is extremely simple and practical in construction and effective in its operation.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. A safety catch comprising a body member having an attaching base and hook-shaped portion with a groove in its outer peripheral face, and a guard member longitudinally slidably mounted in said groove.
2. A safety catch comprising a body member having an attaching base, and a hook-shaped portion with a groove in its outer face having overhanging side walls, and a hooked-shaped guard member slidably mounted in said groove and having an operating handle at one end thereof.
3. A safety catch comprising a body member having an attaching base, and a hook-shaped portion with a groove in its outer face having overhanging side walls, a guard member slidably mounted in said

groove limited in its opening and closing movements by said base portion.

4. A safety catch comprising a body member formed of sheet stock folded to form a relatively enlarged broad supporting base, a hook-shaped portion at its opposite end with side walls turned inwardly to overhang and provide a groove about the outer peripheral face of the hook portion, and a guard member semi-circular in cross section slidably mounted in said groove and adapted to be moved to either open or close the mouth of the hook.

5. A safety catch comprising a body member formed of sheet stock folded to form a broad supporting base and substantially U-shape in cross section, a hook-shaped portion at its opposite end with side walls turned inwardly to overhang and provide a groove about the outer peripheral face of the hook portion, and a guard member having reduced side edges slidably mounted beneath the overhanging of said groove and adapted to be moved to either open or close the mouth of the hook.

In testimony whereof I affix my signature.

EUGENE MOREHOUSE.
